his attorney.

UNITED STATES PATENT OFFICE.

FRANK W. WOLFF, OF PARNASSUS, PENNSYLVANIA. ASSIGNOR TO P. H. MURPHY COMPANY, OF PARNASSUS, PENNSYLVANIA, A CORPORATION OF PENNSYLVANIA.

CARLINE.

1,247,776.

Specification of Letters Patent. Patented Nov. 27, 1917.

Application filed January 16, 1917. Serial No. 142,583.

To all whom it may concern:

Be it known that I, FRANK W. WOLFF, a citizen of the United States, and a resident of Parnassus, Pennsylvania, have invented 5 a new and useful Improvement in Carlines, of which the following is a specification.

This invention relates to forged steel carlines for freight cars, and particularly to carlines made from commercial shapes such 10 as I-bars, channels and Z-bars. The objects of the invention are to produce a light, strong, inexpensive carline, which will take up little head room in the car and which does not require the side plates to be deeply 15 notched where its ends are secured to them.

Further objects and details of the invention appear in the following description of the carline shown in the accompanying drawings. For a further statement of what 20 the invention consists in, reference is made to the appended claim.

In the drawings, wherein the same reference characters are used to designate the same or similar parts in the several views,

25 Figure 1 is a plan view of an end portion of a carline embodying my invention;

Fig. 2 is a side elevation of the same;

Fig. 3 is a vertical cross-sectional view of the carline taken on the line 3-3 in Fig. 2, 30 looking in the direction indicated.

The carline 39 shown in the drawings comprises an I-section member arranged with its web vertical, and bent downward on each side of the middle to conform to the pitch 35 of the car roof. The ends of the carline are cut off square and its top flange has its edges bent up between the seats for the ridge pole and purlins to position these members where they belong. The end portion of the

web is split lengthwise half-way between the 40 top and bottom flanges in about as far as the seat for the outside purlin, or farther. The two split portions of the web are lapped for their full width at the ends of the carline, and are securely riveted together. 45 This arrangement causes the top and bottom flanges to converge toward the ends of the carline, and diminishes the height of the carline at the eaves.

A separate end bracket member 40, which 50 has a bifurcated stem portion 41 arranged with one branch on each side of the web of the carline, is securely riveted to each end of the carline 39 for securing it to the side plates.

55 It is evident that further modifications of the invention can be made, and the invention is not restricted to the form shown.

I claim as my invention:

In combination with a car, a carline comprising a main member having top and bottom flanges, and a web disposed vertically, said web terminating at the inner sides of the side plates, and the ends of said web being split lengthwise and the split portions 65 lapped and riveted together at their ends whereby said flanges converge toward the ends of the carline, and extension portions projecting over the side plates in line with said top flange to support said carline from 70 the side plates, said extension portions comprising bifurcations embracing said lapped split portions and riveted thereto by the rivets which secure said split ends together.

Signed at New Kensington, Pa., this 8th 75 day of January, 1917.

FRANK W. WOLFF.
